Inventor:
Roy Granville Sands
134 Jones, Oddington, Gloucester
Atty's.

UNITED STATES PATENT OFFICE.

ROY GRANVILLE SANDS, OF WAUKEGAN, ILLINOIS, ASSIGNOR TO FRANK B. COOK COMPANY, OF CHICAGO, ILLINOIS, A CORPORATION OF ILLINOIS.

FUSE.

Application filed April 21, 1919. Serial No. 291,688.

To all whom it may concern:

Be it known that I, ROY GRANVILLE SANDS, a citizen of the United States, residing at Waukegan, in the county of Lake and State 5 of Illinois, have invented new and useful Improvements in Fuses, of which the following is a full, clear, concise, and exact description, reference being had to the accompanying drawing, forming a part of this 10 specification.

My invention relates to improvements in electric fuses of that type known as rechargeable or re-fillable fuses and in which there are provided means for detachably 15 holding the fuse strip in position, so that when the strip becomes destroyed a new strip may be inserted without discarding the entire fuse cartridge.

One of the objects of my invention is to 20 provide a cartridge fuse of this type which shall consist of few simple parts which may be readily assembled and disassembled to permit the easy and ready renewal of the fuse strip.

25 Other objects and advantages of the invention will appear more fully hereinafter.

In the accompanying drawings I have illustrated certain embodiments of my invention, it being understood, of course, that the 30 invention as set forth in the appended claims may take various forms and be embodied in various structures without departing from the spirit thereof. In the drawings—

Fig. 1 is a longitudinal sectional view of 35 one form of fuse embodying my invention;

Fig. 2 is a disassembled view of the fuse 40 illustrated in Fig. 1;

Fig. 3 is a longitudinal sectional view of 45 a fuse of a different type embodying my invention; and

Fig. 4 is a disassembled view of the fuse 50 illustrated in Fig. 3.

In the embodiment illustrated in Figs. 1 and 2, the fuse is of the knife-blade cartridge type and comprises, as illustrated, an insulating cylindrical shell 1, preferably formed of fibre or like insulating material. At each end of this shell there is arranged a metallic ferrule 2. This ferrule is tightly 55 secured on the shell proper in any suitable manner. Within the ferrule there is formed an annular shoulder 3, on which the supporting washer 4 is adapted to rest. This washer is of the same shape as the shell and

ferrule, illustrated as being circular, and 55 completely fills the end of the ferrule. The shoulder 3 is formed below the edge of the ferrule, so that the washer lies within the ferrule. The edge of the ferrule is notched, as at 5, so that the fuse strip 6 can be bent 60 over the edge of the washer and its end 7 lie flat on the outer face of the washer. A loop 8 is formed by the bending over of the fuse strip, and this loop, it will be noted, lies in the notch 5. Adapted to rest upon 65 each washer 4 is a second disc 9 having extended therefrom a knife-blade 10 and provided with an ear 11 also adapted to fit in the notch 5. It will be noted that the notches at the end of the fuse are oppositely 70 disposed, so that the fuse may extend diagonally through the body of the shell. The ears 11 so situate the discs 9 that the knife-blades 10 at each end are parallel. For holding the discs 9 and the washers 4 in 75 position a cap 12 is provided, which is internally screw-threaded and adapted to engage screw-threads on the ferrule 2. This cap is provided with an annular shoulder 13 adapted to engage over the edge of the disc 80 9, and when the cap is screwed home the disc is securely clamped in position and the end 7 of the fuse clamped between the washer 4 and the disc 9, which in effect forms a part of the cap 12. A small observation opening 14 is formed in the disc through which the rating of the fuse— 85 which rating is stamped on the end thereof—may be read.

In Figs. 3 and 4 I have shown a fuse 90 which is not provided with knife-blades such as illustrated in Figs. 1 and 2. In these figures there is provided the same insulating shell 1 having the ferrules 2 fastened on the ends thereof, the ferrules having 95 formed therein an internal shoulder 3 on which the washer 4 is adapted to be placed. The edge of the ferrule is notched, as at 5, and the fuse 6 is adapted to be looped over the edge of the washer, in the 100 same manner as described with respect to Figs. 1 and 2. In Fig. 3, instead of providing a knife-blade and two-part cap, as illustrated in Fig. 1, I have provided a cap 15 which clamps down upon the end of the 105 fuse to clamp the fuse strip between it and the washer 4. This cap is likewise provided with an opening 16 through which the rat-

ing of the fuse may be read. Preferably the cap in both forms of fuses is knurled, as at 17, so that the same may be easily rotated, to screw it on and off the ferrules.

5 Having thus described my invention, what I claim as new and desire to secure by Letters Patent, is:

1. A rechargeable electric fuse comprising an enclosing shell having metallic end pieces, a disc closing each end of said shell, a fuse extending longitudinally of said shell and having its ends bent over and lying flat on said discs, a notch formed in the edge of each of said end pieces to accommodate that portion of the fuse lying outside of the periphery of the disc, and caps secured on the shell end pieces and cooperating to clamp the bent-over portions of the fuse against the faces of the discs.

20 2. In a rechargeable electric fuse, the combination with an enclosing shell having metallic end pieces severally provided with a notch formed in the edge thereof, a fuse extending through said shell having a loop at its ends lying in said notch, a disc covering each of said end pieces fitting in said loop and having a portion of the end of the fuse lying over its outer face, and a cap secured to each end piece and cooperating to clamp the overlapping portion of the fuse against the disc and holding the parts in position.

30 3. The combination with an enclosing shell having a notch in its edge at each end thereof oppositely disposed, a fuse extending through said shell and having a loop in its ends lying in said notch, a disc covering the ends of said shell fitting in said loop and having a portion of the end of the fuse 40 lying over its outer face, and a cap secured on each end of the shell and cooperating to clamp the overlapping portions of the fuse against the disc and holding the parts in position.

45 4. A rechargeable electric fuse comprising an insulating shell body, a metal ferrule secured to each end of said body, a disc engaging each of said ferrules, a fuse extending longitudinally of the shell body and having its ends bent over and lying flat on said discs, said ferrule having a notch formed in the edge thereof to accommodate that portion of the fuse lying outside of the periphery of the disc, and a cap secured to the ferrule and cooperating to clamp the bent-over portion of the fuse against the face of the disc.

50 5. A rechargeable electric fuse comprising an enclosing shell body, a metallic ferrule secured to each end of said body, a disc closing the end of each of said ferrules, a fuse extending longitudinally of said body and having its ends bent over and lying flat on said disc, a notch in the edge of each of said ferrules to accommodate that portion of the

fuse lying outside of the periphery of the disc, and a cap secured on the ferrule and cooperating to clamp the bent-over portion of the fuse against the face of the disc.

6. A rechargeable electric fuse comprising an insulating shell body, a metallic ferrule secured to each end of said body having an internal annular shoulder and a notch formed in its edge, a disc closing each of said ferrules and resting on said shoulder, a fuse 75 extending longitudinally of said body and having its ends bent over and lying flat on said disc, the notch in the edge of said ferrule accommodating that portion of the fuse lying outside of the periphery of the disc, 80 and a cap secured on each ferrule and cooperating to clamp the bent-over portion of the fuse against the face of the disc.

7. A rechargeable electric fuse comprising an enclosing shell having oppositely disposed notches formed in its edges, a disc closing one end of said shell, a fuse extending longitudinally of said shell and having one of its ends bent over and lying flat on the outside of said disc, one of the notches in the edges 90 of said shell accommodating that portion of the fuse lying outside of the periphery of the disc, a second disc having a blade formed thereon bearing on said first disc and having a projection in its periphery fitting in said notch for positioning said blade, and a cap secured on the end of said shell and clamping said discs in position.

8. A rechargeable electric fuse comprising an insulating shell body, a metallic ferrule 100 secured on each end of said body, a disc closing the end of each of said ferrules, a fuse extending longitudinally of said shell and having its ends bent over and lying flat on said discs, a notch in the edge of said shell to accommodate that portion of the fuse lying outside of the periphery of the disc, a second disc having a blade secured thereon bearing on said first disc and having a projection on its periphery fitting in said notch 110 for positioning said blade, and a cap secured on the end of said ferrule and clamping said discs in position.

9. A rechargeable electric fuse comprising an insulating shell body, a metallic ferrule 115 at each end of said body having an annular internal shoulder, a disc arranged within the end of each of said ferrules and resting on said shoulder, a fuse extending longitudinally of said shell and having its ends bent over and 120 lying flat on said disc, a notch in the edge of the ferrule to accommodate that portion of the fuse lying outside of the periphery of the disc, a second disc having a blade arranged within said ferrule and provided with an 125 extension on its periphery fitting within said notch for positioning said blade, and a cap secured on said ferrule and clamping said discs in position.

10. An electric fuse comprising an insu- 130

lating tubular member, a metallic ferrule secured to each end thereof, a closure member engaging each of said ferrules, a fuse extending longitudinally of said tubular member and having its ends bent-over to engage said closure members, an opening being formed intermediate each closure member and its bend in the fuse, a second closure member for each end of said tubular member having a blade portion secured thereto and bearing on said first closure member and provided with means cooperating with the adjacent ferrule for properly positioning said blade portion, and a cap secured to each of said ferrules for clamping the adjacent closure members in position.

11. An electric fuse comprising an insulating tubular member, a metallic ferrule se-

cured to each end thereof, a closure member 20 engaging each of said ferrules, a fuse extending longitudinally of said tubular member having its ends bent-over to engage said closure members, an opening being formed intermediate each closure member and its 25 cooperating ferrule to accommodate the bend in the fuse whereby said tubular member may be closed at each end, a second closure member for each end having a blade secured thereto and covering said first closure 30 member, means for properly positioning said blade portions with respect to each other, and a cap member for clamping each pair of closure members in position and securing them to the ferrules.

In witness whereof, I have hereunto subscribed my name.

ROY GRANVILLE SANDS.
